PATENTED
MARCH 20 1962

United States Patent Office.

SPENCER M. CLARK, OF WASHINGTON CITY, DISTRICT OF COLUMBIA.

Design No. 3,083, dated June 30, 1868.

DESIGN FOR A TRADE-MARK.

The Schedule referred to in these Letters Patent and making part of the same.

TO ALL WHOM IT MAY CONCERN:

Be it known that I, SPENCER M. CLARK, of the city of Washington, in the District of Columbia, have originated a new Design for a Trade-Mark, of which the following is a clear and exact illustration, and which is also shown in the accompanying drawing, forming a part of this specification.

And I do hereby claim as my invention, and desire to secure by Letters Patent—

The said design for a trade-mark, as herein set forth and illustrated.

S. M. CLARK.
